DRIVING ARRANGEMENT FOR LOOMS

Georg Wiget, Arbon, Switzerland, assignor to
Aktiengesellschaft Adolph Saurer, Arbon, Switzerland

Application September 13, 1944, Serial No. 553,919
In Germany July 27, 1943

2 Claims. (Cl. 139—1)

1

This invention relates to driving arrangements for looms provided with one or more supplemental devices, for example, means for reversing the loom and/or means for stopping the loom, when the slay is in corresponding predetermined position.

According to the present invention, the loom is started or stopped by axially shifting an actuating rod which extends across the major part of the width of the loom and by means of which the supplemental devices can also be actuated, in such manner, that to the throwing-in of any of the supplemental devices, corresponds a predetermined shifting or axial rocking movement of the rod in one direction.

Preferably, this actuating rod is spring controlled so as to resist any shifting or axial rocking from a median position corresponding to the condition of rest, and in the various operative positions the rod is secured only in the position for normal operation by an arresting device, whereas from all other positions of adjustment the rod returns automatically into the median position.

In looms provided with a reversing gear and with a supplemental stopping device which is controlled by a movable part of the loom to stop the slay in a predetermined position, these devices are preferably so connected with the actuating rod that as this rod is shifted axially from its position of rest, in the opposite direction to the direction of connecting the normal run, for connecting the reverse and that by rotationally displacing the actuating rod about its longitudinal axis, the supplemental stopping device is rendered operative.

The invention is illustrated by way of example, in the drawings affixed to this specification and forming part thereof, in which:

Fig. 1 is a sectional side elevation of the loom;

Fig. 1a is an end view;

Fig. 2 is a partial plan view, partly in section;

Fig. 3 is a fragmentary front elevation, partly in section, and

Fig. 4 shows a detail in Fig. 3, drawn to a larger scale.

Referring to the drawing and first to Fig. 1: The slay 1, which is arranged for oscillation about the axis of a journal 43 supported in the loom structure, is operatively connected with the gear 46 by the connecting rod 45. The gear 46 meshes on the one hand with a gear 47 keyed on the shaft 48 and on the other hand with a pinion 49 keyed on the shaft 2. This shaft is driven by a motor 6 by means of a coupling which is com-

2

posed of two discs or wheels 3 and 4 and a driving belt 5. The coupling disc 4 which is mounted on the shaft 2 for rotation and axial displacement can be thrown in and out by means of a control lever 7, which is actuated by a rod 8 which in addition through the intermediary of a lever 9 controls a brake band 10 cooperating with the disc 3.

The other end of the rod 8 is operatively connected with a connecting rod 14 by means of a lever 11, the shaft 12 and a lever 13. This rod is pivoted to the crank pin 15 of a crankshaft 16 on which is mounted a gear 18.

On the pin 51 fixed to the gear 18 (Fig. 4) the two spring-acted pawls 17, 17' are arranged for oscillation, the spring 52 inserted between the outer pawl ends tending to press their inner ends onto the circumference of the crankshaft 16. By this arrangement, if the inner pawl ends engage the notches 16'', 16', a rotation of the gear 18 relative to the shaft 16 is prevented from taking place and in this case the gear and the crankshaft operate as a unit. The checks 50, 50', mounted on the gear, limit the stroke of the pawls 17, 17'.

The gear 18 is in mesh with the rack-shaped part 29 of an actuating rod 19 and can be turned in unison with the crankshaft 16 by the axial displacement of the rod 19. However, rotation of the crankshaft 16 under the action of the rack-shaped rod 19 from the lower to the upper dead center position of the crank pin 15 can take place, owing to the provision of a stop 21, in an anticlockwise direction only. The rod 8 further carries a spring 22 (Fig. 1) which controls the coupling and the brake and tends to return the connecting rod 14 and the crank 16 into the lower dead centre position of rest. When the rod 19 is moved towards the right from its position of rest, the gear 18 is operatively connected with the crankshaft 16 by way of the pawls 17, 17' and notches 16'', 16' until pawl 17 meets the stop 21, this position approximately coinciding with the upper dead center position of the pin 15. Any further small movement of rod 19 towards the right, compresses the spring 52 located between the outer ends of the pawls 17, 17'. Since the pawl 17' is fixed in position by the journal 51 and notch 16' and cannot yield, pawl 17 is compelled to swing about the journal 51 until its inner end is withdrawn from the notch 16'' and meets the check 50. During the last part of this movement, however, the crankshaft pin 15 has moved slightly beyond the upper dead center position in anti-clockwise direction and from

this movement on the spring 22 and the stop 21 do not cooperate any more in the sense of stopping the loom but act as a safety device against its stoppage. If the upper dead center position of the crank pin 15 coincided exactly with the operative position, then some additional device would have to be provided for preventing the crankshaft 16 from accidentally rotating from the upper to the lower dead center position, which would stop the loom. Such accidental rotation might be occasioned, for instance, by shocks or concussions arising during operation.

In the device here shown and described, the connecting rod 14 coacting with the crank pin 15, when in the position shown in Figs. 3 and 4, forms together with the line connecting the axes of the pin and the crankshaft a toggle lever which comes to rest against the stop 21. This toggle lever becomes active when the pin 15 moves anticlockwise beyond the upper dead center position and is held, with the aid of spring 22, in the operative position.

A cam disc 27 fixed to the crankshaft 16 serves for connecting the reversing gear by acting upon one of the arms of a double-armed lever 26, the other arm of which is pivoted to a rod 25 the other end of which engages with a double-armed lever 24, carrying a reversing roller 23. A spring 28 on the rod 25 tends to press one of the arms of the double-armed lever 26 against the cam disc 27 and to keep the roller 23 out of engagement with the disc 3 during normal operation.

In the gear box or casing 30 of the loom a flange 29 provided with a stud 29' is so secured that this flange can revolve about the longitudinal axis of the actuating rod 19 but is secured against shifting in the axial direction. An opening 31 in this flange corresponds to the cross section of the rack shaped part 29 of rod 19 and serves at the same time as a bearing for this part. A spring 32 retains the flange 29 and the actuating rod 19 together with it in the median position (position O of the flange stud 29' in Fig. 1).

The slay 1 can be stopped in any position by means of two knives 35, 36, which are actuated by cams 33, 34, seated on the shaft 48, and, in the normal operation of the loom, are reciprocated below and above the nose 37' mounted on the lever arm 37 respectively. The cams 33, 34, are so arranged on the shaft 48 that contact of the shoe 35' of the knife 35 with the cam 33 in its highest position coincides with the rear position (I), contact of the shoe 36' of the knife 36 with cam 34 in its highest position with the forward position (II) of the slay.

The lever arm 37 is fixed on the bar 49 which extends movably through the two arms 38'. The bar 49 carries near one end the nose 37'. The arms 38' are fixed to the bar 41 which extends through the brackets 42, 42' mounted on the casing 30, and so is the arm 38''. The two arms 38' and arm 38'' thus form together a double-armed lever oscillatable about the axis of bar 41. The lever arm 37 can be so rocked by the pin 29' provided on the flange 29, that the nose 37' enters the path of one of the knives 35, 36. According to the position taken by the crankshaft 16, the arm 38'' either acts, during the advance movement, on the pin 16''' mounted on shaft 16, or, during reversal, by way of the auxiliary lever 39, on the pawl 17'.

The driving arrangement operates as follows: By shifting the actuating rod 19 in the direc-

tion of arrow B in Fig. 4, the gear 18 and by means for the spring pawls 17, 17' the crankshaft 16 is rotated anticlockwise until the pawl 17' encounters the stop 21 and is thereby disengaged, 5 while the crank pin 15 shifts from the lower to the upper position, i. e., from rest to operation. At the same time the connecting rod 14 is pulled upwardly, thereby displacing the rod 8 towards the right through lever 13, shaft 12 and lever 11. In consequence thereof the brake band 10 is released and the coupling disc 4 is thrown in by means of the lever 7, while the spring 22 holds back the connecting rod 14 and the crank pin 15 in their respective positions by self-locking effect, as illustrated diagrammatically in Fig. 4.

For reversal, the rod 19 is shifted axially from the position of rest towards the left, as indicated by the arrow A in Fig. 4, whereby the gear 18 is turned in clockwise direction and by means of the pawls 17', 17, seated in their notches 19', 19'', turns the crankshaft 16 in clockwise direction. When this shaft has been rotated through approximately 90 degrees from the lower dead center position (as shown in dot-and-dash lines in Fig. 4), the top end of the double-armed lever 26 has contacted the cam of the disc 27 fixed on the crankshaft 16, being thereby turned anticlockwise and pulling the rod 25 towards the right against the action of spring 28. The bell crank lever 24 is rocked clockwise and the roller 23, which, while the motor is running, constantly rotates in the direction of the arrow, is forced against the disc 3, turning the shaft 2 in reversal direction. To this end the cam disc 27 is so arranged on the shaft 16 that the reversing roller 23 is thrown in only after the brake band 10 has been loosened but prior to the throwing in the coupling disc 4. The parts are held in the reverse running position by holding rod 19 by hand in the left hand position.

Where in the normal operation of the loom it is desired that the slay be arrested in one of the two end positions I or II, the supplemental stopping device is thrown in. In that case the actuating rod 19 is rocked about its longitudinal axis until the stud 29' on the flange 29 is in either of the positions marked I and II. By this rocking movement of the actuating rod 19 according to the symbol I (Fig. 4) and the consequent movement of the flange 29 into position I (Fig. 1), the knife 35 is moved by the cam 33 so as to meet the nose 37', whereby the slay 1 is arrested in the rear end position. Conversely, by rocking the actuating rod 19 according to the symbol II (Fig. 4) and thus moving the flange 29 into position II (Fig. 1) the knife 36 is moved by the cam 34 so as to meet the nose 37', whereby the slay 1 is arrested in the front dead centre position II. Due to the rocking of the actuating rod 19, the nose 37' on the lever 37 is moved into the path of one of the two knives 35, 36, and the lever 38', 38'', is angularly displaced about its axis, thereby abutting against the stud 16''. By this means the crank pin 15 is displaced beyond the upper dead center position and is returned into the lower dead center position, corresponding to rest, by spring 22.

On the crank pin moving from the upper to the lower dead center position, with the crankshaft being turned clockwise, the gear 18 is disengaged from the crankshaft 16 since the pawl 17' does not oppose itself to such turning movement (Fig. 4). The connecting rod 14 is shifted downwardly, where by the lever 13, 11 is turned

clockwise (Fig. 1) and the rod 8 is now shifted towards the left, whereby the clutch lever 7 is turned anticlockwise and the wheel 4 driven by the belt 5 and rotating freely on shaft 2, is disengaged from the wheel 3 keyed on this shaft. At the same time the rod 8 turns the lever 9 anticlockwise and tightens the brake band 10, causing the wheel 3 to stop. This also arrests the gear 49 keyed to shaft 2 and the slay 1 which is positively connected with this gear by way of connecting rod 45 and gear 46. The actuating rod 19 and gear 18 are then returned to their position of rest by manually shifting the rod towards the left.

In order to arrest the slay, when the movement of the loom is reversed in one of the two end positions I or II, the supplemental lever 39 is rendered operative. In this case the stud 16'' is located beyond the range of the lever 38', 38'' because the gear 18 has been rotated clockwise due to axial shifting of the actuating rod 19 toward the left. The pawls 17, 17' then engage the rests 16' and 16'' respectively and are in the dotted position shown in Fig. 4.

As soon as, due to rocking of the rod 19 by means of the flange 29 and the intermediary lever 31, the nose 37' enters the path of one of the knives 35 or 36, the lever 38', 38'', is rotated about its axis, thereby causing the supplemental lever 39 to bear against the pawl 17', whereby the operative connection between the gear 18 and the crankshaft 16 is interrupted, in consequence whereof, the crankpin 15 is moved by the spring 22 into the lower dead centre position and the loom is stopped.

I wish it to be understood that I do not desire to be limited to the details of construction

shown and described, for obvious modifications will occur to a person skilled in the art.

I claim:

- 5 1. A loom comprising in combination, a loom-ing frame and a slay, means for driving said loom, an actuating rod extending transversely of said frame and arranged for executing a longitudinal movement and an angular circumferential move-ment, means for actuating said driving means through a longitudinal movement of said rod to start and stop operation of the loom, and supplemental mechanism operable by an angular circumferential movement of said rod for stopping the slay in one of its end positions.
- 10 2. A loom comprising in combination, a loom-ing frame and a slay, means for driving said loom, an actuating rod capable of executing two differ-ent kinds of movements, extending transversely of said frame, means for actuating said driving means through a longitudinal movement of said rod to start and stop operation of the loom, a spring arranged for acting on said rod to counteract any change of position of said rod from its mean position corresponding to the condition
- 15 20 25 of rest of the loom, and means arranged for ar-resting and holding said rod only in the position corresponding to normal operation of the loom.

GEORG WIGET.
